DESIGN FOR A FOOD SHREDDER

Fred F. Latshaw, Altadena, Calif.

Application November 6, 1944, Serial No. 116,162

Term of patent 7 years

(Cl. D89—1)

To all whom it may concern:

Be it known that I, Fred F. Latshaw, a citizen of the United States, residing at Altadena, in the county of Los Angeles, California, have invented a new, original, and ornamental Design for a Food Shredder, of which the following is a specification, reference being had to the accompanying drawing, forming a part thereof.

Fig. 1 is a perspective view of the food shredder showing my new design.

Fig. 2 is a top plan view of the same.

Fig. 3 is a bottom plan view of the same.

I claim:

The ornamental design for a food shredder, as shown.

FRED F. LATSHAW.
